(57) **CLAIM**

The ornamental design for a supercharger housing having integrated cooling fins, as shown and described.

DESCRIPTION

FIG. 1 is a bottom perspective view of a supercharger housing having integrated cooling fins in accordance with the present teachings.

FIG. 2 is a top perspective view of the supercharger housing having integrated cooling fins of FIG. 1.

FIG. 3 is a bottom view of the supercharger housing having integrated cooling fins of FIG. 1.

FIG. 4 is a top view of the supercharger housing having integrated cooling fins of FIG. 1.

FIG. 5 is a first side view of the supercharger housing having integrated cooling fins of FIG. 1.

FIG. 6 is a second side view of the supercharger housing having integrated cooling fins of FIG. 1.

FIG. 7 is front view of the supercharger housing having integrated cooling fins of FIG. 1; and,

FIG. 8 is a rear view of the supercharger housing having integrated cooling fins of FIG. 1.

1 Claim, 3 Drawing Sheets
